UNITED STATES PATENT OFFICE

160,242

BRACELET OR SIMILAR ARTICLE

Paul Bardach, Providence, R. I.

Application July 20, 1949, Serial No. 4,012

Term of patent 3½ years

(Cl. D45—4)

To all whom it may concern:

Be it known that I, Paul Bardach, a citizen of the United States, residing at Providence, in the county of Providence and State of Rhode Island, have invented a new, original, and ornamental Design for a Bracelet or Similar Article, of which the following is a specification, reference being had to the accompanying drawing, constituting a part hereof:

The figure is a perspective view of a bracelet embodying my new design.

The opposite side of the hexagonal spinner element has the numerals 5, 6 and 1 thereon so that the numerals on the six sides of the spinner run consecutively from 1 to 6.

I claim:

The ornamental design for a bracelet or similar article, substantially as shown and described.

PAUL BARDACH.
